[57] CLAIM

I claim the ornamental design for a multi-purpose information center, as shown and described.

DESCRIPTION

FIG. 1 is a perspective view of the multi-purpose information center of the present invention;

FIG. 2 is a front view thereof;

FIG. 3 is a top view thereof;

FIG. 4 is a bottom view thereof;

FIG. 5 is a right side thereof with the left side view being a mirror image thereof;

FIG. 6 is a perspective view of a first alternative embodiment of the multipurpose information center of the present invention;

FIG. 7 is a front view of the multipurpose information center of FIG. 6;

FIG. 8 is a top view thereof;

FIG. 9 is a right side view thereof with the left side view being a mirror image thereof; and,

FIG. 10 is a bottom view thereof.

The rear of the multi-purpose information center is unornamented.
